HIGH PRESSURE FLUID CONTAINER

Scott E. Allen, Verona, N. J., assignor to C-O-Two
Fire Equipment Company, Newark, N. J., a cor-
poration of Delaware

Application April 10, 1940, Serial No. 328,807

2 Claims. (Cl. 169—31)

This invention relates to improvements in high pressure fire extinguishing fluid containers.

Under the Interstate Commerce Commission regulations cylinders containing fire extinguishing fluid under high pressure must be retested hydrostatically every five years. This requires removal of the fire extinguishing fluid from the container and recharging of the container. With the containers now in use it is necessary to disconnect the discharge head from the neck of the container in order to remove the syphon tube so that the fluid used in hydrostatically testing the container may completely fill the container for testing and be drained from the container after the test has been made. The weakest part of the discharge head is at a point adjacent to the upper end of the neck of the container and it frequently happens that the discharge head is broken off at this point during an attempt to disconnect the discharge head from the container. Also on account of the construction of the head it is difficult to apply a wrench close to the neck of the container.

It is one of the objects of my invention to avoid the necessity of removing the discharge head from the container for the hydrostatic testing operation. In accordance with this invention this has been avoided by providing the bottom end of the container with a small threaded opening to receive a threaded closure plug which may be removed to completely fill the container with water and to drain all of the water used in the testing operation from the container so that the testing may be done without disconnecting the discharge head from the neck of the container.

It is a further object of my invention to provide the container with a foot so as to support the bottom end of the container above the floor to protect the threaded closure plug.

Other objects of the invention will appear from the following description taken in connection with the single figure of the drawing which is a vertical diametral section through a container embodying my invention.

A container of the usual shape is shown at 10. Mounted on the container is the usual discharge head which comprises a body 11 provided with a reduced portion 12 threaded into the neck 13 of the container. This body is formed with a discharge bore 14, which is normally closed by a sealing disk 15 secured against a seat in the bore by a tubular plug 16, the head being provided with a puncturing element 17 operated by a hand-wheel 18 by means of which the sealing disk may be punctured to permit the discharge

5 of the fluid within the container. Below the sealing disk the body 11 may be provided with the customary safety plug 20 and the filling fixture 21. Threaded in the lower end of the body 11 and projecting close to the bottom end of the container is the usual syphon tube 26.

10 For the purpose of avoiding the necessity of removing the discharge head and syphon tube from the container for hydrostatically testing the container I provide the bottom end of the container with a small threaded opening 28 for receiving a threaded closure plug 29 which may be tapered as shown to provide a seal tight fit and which because of its small diameter is much 15 more readily removed from the container than is the large diameter threaded portion of the body threaded in the neck of the container. When it is desired to test the container the fire extinguishing fluid therein may be removed by 20 discharging and then the closure plug 29 may be removed and the container filled completely with water for testing purposes. After the test has been made all of the water can be drained out through the opening 28. After this is done the 25 closure plug 29 is threaded in the opening 28 and the container may then be recharged in the usual way.

30 In order to make provision for supporting the container in upright position on the floor or the 35 like, I provide the container with a foot ring 30 which may be of cylindrical form and may be shrunk on the container. This foot is preferably continuous circumferentially and is of such height as to support the head of the closure plug 29 the necessary distance from the floor to prevent 40 injury to the plug. The foot 30 also protects the closure plug 29 against sidewise impacts during transportation. It also protects the threads of the closure plug against moisture, etc. which might cause the same to rust and interfere with the easy removal thereof.

45 While I have disclosed but one form of my invention, it is to be understood that modifications thereof will be suggested to those familiar with this art after understanding my invention and that I reserve the right to all such changes as fall within the principle of this invention and the scope of the appended claims.

I claim:

50 1. In combination with a container provided with a bottom wall having a concave inner surface, a discharge head threaded in the neck of the container and a syphon tube supported in the discharge head and projecting to a point close to the bottom wall of the container, of a clo-

sure plug for the container threaded in the bottom wall of the container in a position opposite the lower end of the siphon tube permitting the container to be filled completely with fluid for testing purposes without the removal of the discharge head and siphon tube, and the container, siphon tube and discharge head to be drained of all of the testing fluid.

2. In combination with a container having a bottom wall with a concave inner surface, a discharge head secured in the neck of the container

5 and a siphon tube connected in the bore in the discharge head and extending to a point near the center of the bottom wall of the container, of a closure plug threaded in the bottom wall of the container opposite the lower end of the siphon tube for removal for filling the container, siphon tube and discharge head with fluid for hydrostatic testing of the container and for draining testing fluid from the container, siphon tube and discharge head after the test has been made.

SCOTT E. ALLEN.
